United States Patent Office

Des. 222,614
Patented Nov. 16, 1971

222,614

LIFT TRUCK BODY

Warner K. Brown, 111 Shadywood Lane, Battle Creek,
Mich. 49015, and Darrell C. Fuller, 1602 Orchard
Lane, Marshall, Mich. 49068

Continuation-in-part of design application Ser. No. 18,756,
Aug. 19, 1969. This application June 10, 1970, Ser.
No. 23,433

Term of patent 14 years

Int. Cl. D12—05

U.S. Cl. D14—3

FIG. 1

Des. 222,614

PAGE 2

FIG. 2

Des. 222,614

PAGE 3

FIG. 3

Des. 222,614

PAGE 4

FIG. 4

FIG. 5

FIG. 1 is a right side view of a lift truck body, showing our new design;

FIG. 2 is a right front quarter perspective view thereof;

FIG. 3 is a right rear quarter perspective view thereof;

FIG. 4 is a rear view thereof; and

FIG. 5 is a front view thereof.

The elements shown in broken lines are included for illustrative purposes only. The undisclosed side is substantially the same as the side shown.

This application is a continuation-in-part of our application Ser. No. D. 18,756 filed Aug. 19, 1969, now abandoned.

We claim:

The ornamental design of a lift truck body, as shown and described.
